(57) CLAIM

The ornamental design for a pill box, as shown and described.

DESCRIPTION

FIG. 1 is a front, right and top perspective view of a pill box, showing my new design;

FIG. 2 is a rear, left and bottom perspective view thereof;

FIG. 3 is perspective view of the pill box in a using state;

FIG. 4 is a front view thereof;

FIG. 5 is a rear view thereof;

FIG. 6 is an enlarged left side view thereof;

FIG. 7 is an enlarged right side view thereof;

FIG. 8 is a top plan view thereof; and,

FIG. 9 is a bottom plan view thereof.

The broken lines shown in the drawings illustrate portions of the pill box that form no part of the claimed design.

1 Claim, 9 Drawing Sheets
